UNITED STATES PATENT OFFICE.

CHARLES R. JEDLICKA, OF PALO ALTO, CALIFORNIA.

SANITARY TOILET-SEAT COVER.

Application filed July 24, 1923. Serial No. 653,540.

To all whom it may concern:

Be it known that I, CHARLES R. JEDLICKA, a citizen of the United States, residing at Palo Alto, in the county of Santa Clara and State of California, have invented new and useful Improvements in Sanitary Toilet-Seat Covers, of which the following is a specification.

This invention relates to lavatory supplies and more particularly to a sanitary toilet seat cover.

The primary object of this invention resides in providing a sanitary cover for toilet seats to prevent propagation of diseases.

Another object of this invention resides in the provision of a sanitary cover for toilet seats adapted to be utilized with fastening elements so it can be removably fastened to the toilet seat to completely cover the same.

A still further object of this invention resides in the provision of a sanitary cover for toilet seats formed of such material that it can be disposed of through the waste pipe of the flush bowl after use.

In addition to the foregoing objects, this invention resides in the provision of a cover for toilet seats formed of such material that it can be treated with an antiseptic preparation to render it sanitary and, thereby, protect individuals from contamination.

Aside from the aforesaid objects, this invention resides in the provision of a sanitary cover for toilet seats embodying simple means whereby it can be readily secured to a toilet seat in temporary fixed relation thereto.

With the above and other objects in view, this invention resides in certain novel features of construction, arrangement and combination of elements to be hereinafter more particularly set forth in the specification, illustrated in the accompanying drawings and pointed out in the appended claim.

In the accompanying drawings forming a part of this application:

Fig. 1 is a plan view of a toilet seat showing the elements of this invention disposed thereon.

Fig. 2 is a longitudinal sectional view thereof on line 2—2 of Fig. 1.

Fig. 3 is a cross-sectional view thereof on line 3—3 of Fig. 1.

Fig. 4 is a detail plan view of the sanitary cover removed from the toilet seat.

Fig. 5 is a similar view thereof showing the sanitary cover as being folded for storage in a convenient container.

Fig. 6 is a detail plan view of a portion of the seat cover showing one of the fastening eyelets.

Fig. 7 is an enlarged detail sectional view on line 7—7 of Fig. 1.

In the present embodiment of this invention, the numeral 5 designates a sanitary toilet seat cover, which is preferably made of tissue paper chemically treated with an antiseptic preparation.

The aforesaid sanitary toilet seat cover is preferably made to conform somewhat to the general configuration of standard toilet seats, one type of which is illustrated at T, and is so proportioned as to readily assume the curvatures of the toilet seat to completely cover that area thereof in close proximity to an individual occupying the same.

Carried by the toilet seat T and projecting above the surface thereof are fastening elements 6, which are disposed to readily enter eyelets 7 of the sanitary seat cover to prevent it from sliding on the toilet seat.

In order to reinforce that area of the sanitary toilet seat cover which is engageable by the fastening elements 6, apertured tabs 8 are secured to the opposite sides of the tissue, the same being so disposed that their aligned apertures (forming the eyelets 7) will readily permit the heads of the fastening elements 6 to puncture that area of the tissue bound by the walls of the apertures so the tissue will be relieved of any strain at the points selected to secure it to the toilet seat. By securing the tabs 8 over the tissue as aforesaid, the fastened areas of tissue tightly surround the fastening elements, to completely close the apertures surrounding the fastening elements.

With this invention fully set forth, it is manifest that a cheap, sanitary and durable cover for toilet seats is provided and, while

the present disclosure imparts my present conception of this invention, the right is reserved to resort to such changes as come within the scope of the claim.

5 Having thus described my invention, what I claim and desire to protect by Letters Patent is:

A sanitary seat cover comprising a sheet

of material having an opening therein, and elongated reinforcing tabs fixed to said cover 10 and in pairs on opposite sides of the cover and having elongated apertures in alignment, said elongated apertures lying longitudinally of the cover.

In testimony whereof I affix my signature.

CHARLES R. JEDLICKA.
